(57) **CLAIM**

The ornamental design for a container for cosmetics as shown and described.

DESCRIPTION

FIG. 1 is a perspective view of a container for cosmetics according to the claimed design.

FIG. 2 is a front view of the container for cosmetics.

FIG. 3 is a rear view of the container for cosmetics.

FIG. 4 is a top view of the container for cosmetics.

FIG. 5 is a bottom view of the container for cosmetics.

FIG. 6 is a right side view of the container for cosmetics; and,

FIG. 7 is a left side view of the container for cosmetics.

The broken lines in the drawings depict portions of the container for cosmetics that form no part of the claimed design.
